UNITED STATES PATENT OFFICE

152,187

DESIGN FOR A HAND BLOWTORCH

Benjamin Franklin Burnham, Huntington Woods,
Mich., assignor to Kerr Manufacturing Company, Detroit, Mich., a corporation of Michigan

Application April 7, 1947, Serial No. 138,206

Term of patent 3½ years

(Cl. D54—13)

To all whom it may concern:

Be it known that I, Benjamin Franklin Burnham, a citizen of the United States of America, residing at Huntington Woods, in the county of Oakland and State of Michigan, have invented a certain new, original, and ornamental Design for a Hand Blowtorch, of which the following is a specification, reference being had therein to the accompanying drawing, forming a part thereof, wherein:

Fig. 1 is a side elevational view of a hand blowtorch showing my new design;

Fig. 2 is a front elevational view; and

Fig. 3 is a top plan view thereof.

I claim:

The ornamental design for a hand blowtorch, substantially as shown.

BENJAMIN FRANKLIN BURNHAM.
